(57) **CLAIM**

I claim the ornamental design for front, back, sides and bottom portions of a scooter, as shown and described.

DESCRIPTION

FIG. 1 is a top, rear, left-side perspective view of a front, back, top, sides and bottom portions of a scooter showing my new design;

FIG. 2 is a front elevational view thereof;

FIG. 3 is a top plan view thereof; and,

FIG. 4 is a left-side elevational view thereof, the right-side elevational view being a mirror image, except for a stand at the lower right.

The portions of the bottom that are not shown are disclaimed.
